CONTINUOUS INTERLEAVED ENVELOPE
ASSEMBLY

Louis F. Hageman, Niagara Falls, N. Y., assignor
to American Sales Book Company, Inc., Niagara
Falls, N. Y., a corporation of Delaware

Application April 27, 1939, Serial No. 270,325

11 Claims. (Cl. 282—12)

This invention relates to improvements in manifolding assemblies of the type including long continuous interleaved record strips with interleaved transfer material, and adapted for use for transfer inscription either by manual means or in connection with various forms of writing machines such as typewriters, billing machines, tabulators, teletypewriters, autographic registers, and the like. More particularly, the invention relates to an improved arrangement of envelopes interleaved in inscription transfer relation with the record strips of the manifolding assembly.

It is a general object of the invention to provide an improved means for mounting and assembling envelopes in transfer relation with manifolding assemblies of the class mentioned.

A further object of the invention is to provide an improved means for connecting envelopes in series formation in manifolding assemblies of the class mentioned, whereby the envelopes are adapted to receive transfer inscriptions simultaneously with the record strips.

A further object of the invention is to provide an improved means of mounting and retaining a series of connected envelopes in transfer relation in manifolding assemblies of the class mentioned whereby the envelopes may be very readily separated from the assembly following completion of the inscriptions.

A further object is to provide an improved means for attaching the series connected envelopes in assembled relation with the other constituent elements of the manifolding assembly, and for releasing them upon severance of a single manifolding set or group of sheets from the complete assembly.

Other objects and advantages of the invention will be in part pointed out in the following detailed description of an illustrative but preferred embodiment of the invention and will be in part obvious as the disclosure proceeds.

The invention accordingly comprises the features of construction, combination of elements, and arrangement of parts, which will be exemplified in the construction hereinafter set forth and the scope of the application of which will be indicated in the claims.

For a more complete disclosure of the nature, objects, and advantages of the invention, reference is had to the following detailed description and to the accompanying drawings, in which:

Fig. 1 is a perspective view of a record assembly or manifolding assembly embodying the invention;

Fig. 2 is an enlarged partially diagrammatic

detail perspective view of the assembly shown in Fig. 1, the assembly parts being widely separated to reveal the structure and arrangement;

Fig. 3 is a partially diagrammatic transverse vertical sectional view of the assembly;

Fig. 4 is a fragmentary detail perspective view of the structure and arrangement of the series envelopes; and

Fig. 5 is a detail perspective view of an alternative form of record strip.

Referring to the drawings for a detailed description of the illustrative embodiment of the invention, the manifolding assembly includes a plurality of continuous or traveler record strips 10 interleaved in manifolding relation with each other. Interleaved in transfer relation with the record strips is transfer material positioned for transferring the inscriptions made on the upper or original record strip 10 to the underlying record surfaces. While the transfer material may be thus interleaved in various ways, it is herein disclosed in the form of continuous traveler transfer strips 11 coextensive in length with the record strips 10. The transfer strips 11 may be coated with transfer material as desired to transfer the inscriptions to the underlying record surfaces, being shown as coated on their under surfaces with carbon transfer material 12 so as to transfer the inscriptions to the underlying upwardly directed record surfaces. Portions of the transfer material 12 may be omitted when it is desired to omit portions of the transfer inscriptions that are made upon the original record strip as described more fully below.

As shown, the record strips 10 are preferably slightly wider than the transfer strips 11, having lateral extensions providing feed bands 13 extending longitudinally of the assembly and having pin feed apertures 14 arranged in series therealong. These feed bands lie outwardly beyond the adjacent edges of the carbon and transfer strips so that the pin feed mechanism of the writing machine engages only the feed bands of the record strips. The feed bands may be easily

separated from the record strips by the use of longitudinal weakened severance lines 10a. These feed bands may be provided only at one longitudinal assembly edge as shown in Fig. 1, or they may be positioned at both longitudinal assembly edges as later described in connection with Fig. 5.

Both the record strips 10 and the transfer strips 11 are ordinarily formed with transverse weakened severance lines along which the strips may be severed. Such severance lines 15 divide

the record strips into record leaves, while similar weakened lines 16 divide the transfer strips into transfer sheets respectively interleaved between the record sheets. The weakened severance lines 15 and 16 are thus arranged in depthwise groups spaced longitudinally along the assembly. These lines may be weakened by perforating, scoring, slitting, or otherwise weakening the paper of the strips in known manner.

The severance lines 16 of the carbon strips have deviating portions 17 deviating longitudinally of the assembly from other parts of the lines 16 and from the lines 15 of the record strips. These longitudinally deviating line portions 17 are preferably weakened to a greater extent than the remainder of the lines as by providing elongated slits or cuts extending entirely through the paper. These deviating line portions provide grip tabs 18 projecting from the adjacent edges of the carbon sheets. The purpose of this grip tab structure is to provide means for selectively separating the carbon sheets of a severed record set or unit from the record sheets thereof in a manner as fully described in the Conklin Patent No. 2,083,295, issued June 8, 1937 to which reference is made for a more complete disclosure of this feature.

For attaching the constituent elements of the assembly together, fastening devices are provided substantially as set forth in the Conklin patent mentioned. These fastening devices include staples or filamentary binders 19 longitudinally spaced at intervals along the assembly and engaging and extending through the assembly strips. These staples 19 may be constructed of textile thread or light metallic wire and are positioned directly upon the severance lines 15 of the record strips and extend through the assembly from top to bottom thereof. They will thus be freed from the record strips upon severance along the lines 15. The staples pass through the bases of the grip tabs 18 of the carbon sheets so as to hold said sheets together after separation thereof from the assembly as fully described in the Conklin patent.

The manifolding assembly is preferably folded in zigzag formation along the transverse severance lines to provide a zigzag folded supply pack 20 which is convenient for handling and loading into the various writing machines. The assembly is shown in Fig. 1 as being thus folded only on each alternate transverse line 15, thus presenting two record leaves at the top of the zigzag pack or in other words, the assembly is folded "two up." It is obvious, however, that it may be folded "one up" or along each of the transverse weakened lines, or in any other desired manner.

Interleaved in manifolding relation with the record and transfer strips is an envelope series 21 which is shown in detail in Fig. 4. This envelope series includes a multiplicity of individual envelopes 22, which may be of any preferred known construction, having receiving openings 23 leading to the inner receiving compartments and having closure flaps 24 adapted to fold over the openings 23. For this purpose the flaps may be provided at their marginal surfaces with a coating of adhesive material to seal the flaps in closed positions. The envelopes may be constructed of paper or similar sheet material.

Each of the sealing flaps 24 of the envelopes has an attaching extension or part 25 extending into overlapping relation with the adjacent edge or marginal part of the next envelope in the series and attached thereto. While the attachments

25 may be secured in any desired manner, it is convenient to coat them with an adhesive material and to cause them to adhere to the adjacent envelopes, thus attaching all of the envelopes together in a continuous series which preferably extends throughout the length of the manifolding assembly. These attachments are preferably positioned at the longitudinal center line of the envelope assembly. The attaching part 25 of each envelope flap 24 is preferably separated from the main part of the flap by transverse weakened severance lines 26 which also may be formed by perforating, scoring, slitting, etc., thus providing for ready detachment of the envelopes from each other.

As shown in Figs. 2 and 3 this series of connected envelopes is positioned in manifolding relation in the record assembly with the upper inscription receiving surfaces in transfer relation with the lower surface of the upper transfer strip 11. The longitudinal spacing of the severance lines 26 of the envelope attachments is substantially the same as that of the severance lines 15 and 16 of the record and transfer strips, the lines 26 being positioned respectively substantially in depthwise alignment with the lines 15 and 16. Thus it will be seen that the filamentary binders 19 will extend directly through the corresponding severance lines 26, thus binding the envelope series in its correct inscription receiving relation in the assembly. As shown in Fig. 3 the envelopes 22 are slightly shorter transversely of the assembly than the width of the record strips 10 so that the envelope ends are protected and positioned so as to avoid engagement with or catching upon external objects during handling of the assembly. The envelope series will be folded into the supply pack 20 in the manner above described for the record strips. It will be noted that the envelopes 22 of the series are in the form of units having longitudinally spaced body portions separate from each other, these body portions being connected by the envelope closure flaps extended in connecting positions 45 away from their normal closing positions. By means of this structural arrangement envelopes closely approximating standard construction may be utilized. The fastening devices 19 are positioned intermediate the adjacent envelope body parts respectively so as to avoid any mutilation thereof by the fastening devices.

From the foregoing description it will be seen that each envelope 22 of the envelope series will be positioned in one of the sets of record and transfer sheets in position to receive inscriptions at the time that the record sheets are inscribed. While this improved record assembly including the envelope series may be utilized for recording various business transactions, the utilization thereof for handling payrolls is particularly mentioned. For this purpose the record sheets of the record strips 10 may be provided with blank forms 27 for receiving the data in connection with the payroll so as to maintain complete records. The envelopes may thus be utilized for containing the currency or the like together with one of the inscribed record sheets giving the complete data. Many other uses will be suggested to those familiar with the art, especially for recording business transactions wherein a name and address is required, together with a relatively small amount of additional data, and for mailing purposes.

After the data has been inscribed on the blank form of the leading record set of assembly sheets

and envelopes, either manually or by means of an appropriate writing machine, the inscribed set can be readily severed as a unit from the complete assembly by tearing along the group of weakened severance lines 15, 16, 26. The set of record and transfer leaves or sheets thus severed will thus include one of the envelopes 22 which has been properly inscribed on its upper inscription receiving surface. The carbon or transfer sheets of the severed set may then be very easily separated from the record sheets and envelope by gripping the tabs 18 projecting at one side of the assembly, and at the same time gripping the opposite marginal portions of the record sheets and of the envelope in line with the marginal notches or openings of the carbon sheets formed by removal of the tabs 18, in the manner fully described in the Conklin patent above referred to. The envelope and record sheets may then be disassembled and the desired contents placed in the envelope after which it may be sealed and delivered.

In some instances it is desired to omit from the envelope surface certain of the inscriptions that are written upon the original record strip 10. In such cases a portion of the transfer coating 12 of the upper transfer strip 11 will be omitted as indicated at 28 in Fig. 2. The area 28 of this transfer strip will be entirely free of transfer material so that a portion of the inscription will not be transferred to the envelope surface. The area 28 is shown as being positioned next to the envelope flap 24, and it may also be extended to overlap a portion of the envelope surface at the bottom of the envelope opposite to its opening 23. Such clean or non-transfer areas 28 may extend entirely across the transfer strip 11 or its bounds may be limited so as to omit the inscriptions as desired. Thus in cases where it is desired to omit from the envelope all data except name and address, this may be readily accomplished by extending the limits of the non-transfer area 28.

As suggested in Fig. 5 each of the record strips 29 of the assembly may be provided with longitudinal feed bands 30 at both of its longitudinal margins. These feed bands are provided with feed apertures 14 as described above. Otherwise the record strips 29 will be similar to the record strips 10 above described and they will be similarly arranged in the manifolding assembly. The envelope series together with carbon strips will be interleaved with two or more of the record strips 29 in the same manner as described above.

Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a manifolding assembly, in combination, continuous interleaved record strips, a plurality of envelopes in series formation and having connections with each other and interleaved in manifolding relation with said record strips, said envelopes having body portions separate from each other and having closure flaps included respectively in said envelope connections and extended in non-closing positions, transverse weakened severance lines arranged in depthwise groups in said strips at a series of longitudinally

spaced points along the assembly and substantially in depthwise alignment respectively with certain of said envelope connections, and attachments binding said strips and envelopes together at spaced points along the assembly and positioned respectively directly on said severance lines and at points respectively intermediate said body portions of respective adjacent envelopes.

2. In a manifolding assembly, in combination, 10 continuous interleaved record and transfer strips, a plurality of envelopes having body portions separate from each other and longitudinally spaced apart, said envelopes being arranged in series formation and interleaved in manifolding relation with said record and transfer strips, connections bridging the spaces between respectively adjacent envelope body parts and connecting the envelopes together in the series, transverse weakened severance lines arranged in depthwise groups in the strips at a series of longitudinally spaced points along the assembly and substantially in depthwise alignment respectively with certain of said envelope connections, and longitudinally spaced filamentary binders spaced along the assembly for binding the assembly parts together and being positioned respectively substantially upon said transverse weakened severance lines and respectively intermediate said body portions of adjacent said envelopes.

3. In a manifolding assembly, in combination, continuous interleaved record and transfer strips, a series of envelopes having body portions separate from each other and longitudinally spaced apart, said envelopes being interleaved in manifolding relation with said record and transfer strips, transverse weakened severance lines in the strips arranged in depthwise groups at a series of longitudinally spaced 30 points along the assembly and substantially in depthwise alignment respectively with certain of said envelope connections, and longitudinally spaced filamentary binders spaced along the assembly for binding the assembly parts together and being positioned respectively substantially upon said transverse weakened severance lines, said binders being positioned respectively intermediate adjacent envelope body parts and having readily breakable connection respectively with said envelope connections so as to retain the envelopes in position in the assembly and to release them upon breaking of said breakable connections.

4. In a manifolding assembly, in combination, 55 continuous interleaved record strips, a series of envelopes having connections with each other and interleaved in manifolding relation with said record strips, each said envelope connection including an envelope closure flap in extended non-closing position and having a readily detachable attachment including a transverse weakened severance line, transverse weakened severance lines in the record strips arranged in depthwise groups at a series of longitudinally spaced points along the assembly and substantially in depthwise alignment respectively with said weakened lines of said envelope connections, and longitudinally spaced filamentary binders for binding the assembly parts together and respectively positioned substantially on said transverse weakened severance lines of the strips and envelope connections.

5. In a manifolding assembly, in combination, 70 continuous interleaved record strips, and a series of envelopes having connections with each other

and interleaved in manifolding relation with said record strips, said envelope connections including attaching flaps projecting respectively from the envelope edges and having connection with the adjacent envelopes, and attachments connecting the said strips and envelopes together at spaced points along the assembly and including connections with the respective said envelope connections.

6. In a manifolding assembly, in combination, continuous interleaved record strips, a series of envelopes having connections with each other and interleaved in manifolding relation with said record strips, said envelope connections including attaching flaps projecting respectively from the envelope sealing flaps and having connection with the adjacent envelopes, said attaching flaps having weakened severance lines, and filamentary binders for binding the assembly parts together and respectively passing through said weakened severance lines of said attaching flaps.

7. In a manifolding assembly, in combination, continuous interleaved record and transfer strips, and a series of envelopes having connections with each other and interleaved in manifolding relation with said record and transfer strips, each of said envelopes being positioned in inscription transfer relation with one of said transfer strips which has parts of its transfer face free of transfer material for selective transfer inscriptions to the envelope, said envelope connections including attaching flaps projecting respectively from the envelope edges and having connection with the adjacent envelopes, and attachments connecting the said strips and envelopes together at spaced points along the assembly and including connections with the respective said envelope connections.

8. In a manifolding assembly, in combination, continuous interleaved record and transfer strips, a series of envelopes having connections with each other and interleaved in manifolding relation with said record and transfer strips, each of said envelopes being positioned in inscription transfer relation with one of said transfer strips which has parts of its transfer face free of transfer material for selective transfer inscriptions to the envelope, said envelope connections including attaching flaps projecting respectively from the envelope edges and having connection with the adjacent envelopes, said attaching flaps having transverse weakened severance lines, and filamentary binders for binding the assembly parts

together and passing through said weakened severance lines of said attaching flaps.

9. In a manifolding assembly, in combination, continuous interleaved record and transfer strips, a series of envelopes having connections with each other and interleaved in manifolding relation with said record and transfer strips, each of said envelopes being positioned in inscription transfer relation in the assembly, said envelope connections respectively including envelope closure flaps in extended non-closing positions in the assembly and having connection with respectively adjacent envelopes, and attaching means for the assembly parts respectively positioned between adjacent envelopes of said series.

10. In a manifolding assembly, in combination, continuous interleaved record strips, a plurality of envelopes in series formation and having connections with each other and interleaved in manifolding relation with said record strips, said envelopes having body portions separate from each other and having closure flaps included respectively in said envelope connections and extended in non-closing positions, transverse weakened severance lines arranged in depthwise groups in said strips at a series of longitudinally spaced points along the assembly, and transverse weakened severance lines positioned respectively in said envelope connections and in substantially depthwise alignment respectively with said severance lines of the strips.

11. In a manifolding assembly, in combination, continuous interleaved record strips, a plurality of envelopes in series formation and having connections with each other and interleaved in manifolding relation with said record strips, said envelopes having body portions separate from each other and having closure flaps included respectively in said envelope connections and extended in non-closing positions, transverse weakened severance lines arranged in depthwise groups in said strips at a series of longitudinally spaced points along the assembly, transverse weakened severance lines positioned respectively in said envelope connections and in substantially depthwise alignment respectively with said strip severance lines, and attachments binding said strips and envelopes together at spaced points along the assembly and positioned respectively directly on said severance lines of the strips and envelope connections.

LOUIS F. HAGEMAN.

CERTIFICATE OF CORRECTION.

Patent No. 2,264,078.

November 25, 1941.

LOUIS F. HAGEMAN.

It is hereby certified that error appears in the printed specification of the above numbered patent requiring correction as follows: Page 3, second column, line 37, claim 3, after the comma and before "transverse" insert --connections connecting said envelopes in the series and bridging the spaces between respectively adjacent envelope body parts,--; and that the said Letters Patent should be read with this correction therein that the same may conform to the record of the case in the Patent Office.

Signed and sealed this 6th day of January, A. D. 1942.

(Seal)

Henry Van Arsdale,
Acting Commissioner of Patents.
